FRANCIS D. PASTORIUS, OF PHILADELPHIA, PENNSYLVANIA.

Design No. 3,301, dated December 29, 1868.

DESIGN FOR A MACHINE-FRAME OR HOUSING.

The Schedule referred to in these Letters Patent and making part of the same.

To all whom it may concern:

Be it known that I, FRANCIS D. PASTORIUS, of the city of Philadelphia, and State of Pennsylvania, have originated and designed a new Pattern for a Machine-Frame or Housing, of which the following is a full, clear, and exact description, reference being had to the accompanying drawings, making part of this specification, in which—

Figure 1 is a side view, and

Figure 2, an end view.

Similar letters refer to similar parts in the two views.

The housing or frame is constructed with its sides A and B, fig. 2, joined together in the casting by the webs *a*, at both ends.

The design consists in the configuration of the sides A and B, as follows:

The verticals *b* are perpendicular, and connected at their upper ends by the arch *c*. Their lower ends terminate in the square or oblong feet *d*. The outer edge of the verticals and arch have a round bead *e* their entire length. The inner edge of the verticals and arch is as follows: Beginning at the top with the Gothic arch *f*, from the ends of which the lines *g g* extend

outwardly in contrary directions, and connect with the *cyma-reversa* curves *h*, the ends of which in turn connect with the curved projections *l l*, on both sides. The remaining parts of the inner edge consist of the verticals *b*, as shown.

The housing or frame, as shown, can be used for any of the various light machines in which the cutters or knives are required to move in a direct vertical line, by means of guides, which are formed in between the sides A and B, as, for instance, vegetable-cutting machines, root-cutters, and tobacco-machines.

What I claim as my invention, and desire to secure by Letters Patent, is—

The design for a machine-frame or housing, herein set forth.

In testimony whereof, I hereunto sign my name to this specification, in presence of two subscribing witnesses.

FRANCIS D. PASTORIUS.
